UNITED STATES PATENT OFFICE.

JOHN WILLIAM AULSON, OF LYNN, MASSACHUSETTS.

LEATHER-GRAINING MACHINE.

Application filed May 18, 1923. Serial No. 639,829.

To all whom it may concern:

Be it known that I, JOHN W. AULSON, a citizen of the United States of America, and a resident of Lynn, in the county of Essex 5 and State of Massachusetts, have invented certain new and useful Improvements in Leather-Graining Machines, of which the following is a specification.

This invention relates to machines for 10 graining, boarding or softening hides and skins after they have been tanned, and its object is the production of a power-driven machine which will treat the hide or skin in a manner similar to that in which it would 15 be treated by a manually actuated board operating thereon.

The invention consists primarily of a hide supporting bed coacting with a revoluble drum adapted to be reciprocated lengthwise 20 of said bed during its rotation.

The invention further consists in certain novel features of construction and arrangement of parts which will be understood readily by reference to the description of the drawings and to the claims to be hereinafter given.

For the purpose of illustrating the invention, one preferred form thereof is illustrated in the drawings, this form having been 30 found to give satisfactory and reliable results, although it is to be understood that the various instrumentalities of which the invention consists can be variously arranged and organized, and that the invention is not 35 limited to the precise arrangement and organization of the instrumentalities as herein shown and described except as required by the scope of the appended claims.

Of the drawings:

40 Figure 1 represents a plan of a machine embodying the principles of the present invention.

Figure 2 represents a side elevation of the same, and

45 Figure 3 represents a transverse section through the drum and showing the mechanism for rotating the drum as it is moved toward the front of the machine.

Similar characters indicate like parts 50 throughout the several figures of the drawings.

In the drawings, 10 is a framework having side bars 11, 11^x extending lengthwise thereof, and provided on each side with a pair 55 of guide members 12 parallel to the side

bars 11, 11^x, each pair of side members 12 being spaced apart.

Between the side guides 12 on opposite sides of the framework 10 are disposed blocks 13 adapted to be reciprocated toward 60 and from the rear of the machine.

In the blocks 13 is revolvably mounted a shaft 14 having a drum secured thereto, said drum consisting of the separated cylindrical end disks 15 and the semi-cylindrical member 16, the opposite ends of which are secured to the disks 15.

The periphery of this semi-cylindrical member 16 has glued or otherwise secured thereto a sheet 17 of material, the outer surface of which is adapted to grip a hide.

To the under face of one side bar 11 on one side of the machine, and on the upper face of the side bar 11^x on the opposite side of the machine are secured the racks 18, 18^x, 75 the teeth of the rack 18 meshing with a gear 19 loosely mounted on the shaft 14 near one end, while the teeth of the rack 18^x mesh with the teeth of a gear 19^x loosely mounted upon the shaft 14 near its opposite end. 80

At the rear of the frame 10 is a drive shaft 20 revolvably mounted in bearings 21 secured to said frame 10. This drive shaft 20 has loosely mounted thereon a pulley 22 on opposite sides of which are the pulleys 85 23 and 24 secured to and revoluble with said shaft 20.

The opposite ends of the shaft 20 have secured thereto the bevel gears 25, each of which meshes with a bevel gear 26 on the 90 rear end of a shaft 27 revolvably mounted in bearings 28 secured to and extending outwardly from the sides of said frame.

Each shaft 27 has a threaded portion 29 between the bearings 28, said threaded portion 29 being threaded to a member 30 having a downwardly extending ear through which an outer end of the shaft 14 extends.

During the rotation of the shaft 27, the threaded portions 29 of the two shafts 27, 100 coacting with the members 30, will cause these members to be moved lengthwise of said threaded portions 29, carrying the blocks 13 and drum 15, 16 therewith.

One of the members 30 has an upwardly 105 extending arm 31 which in its travel is adapted to come into contact with the collars 32, 33 secured to a rod 34 movable lengthwise in bearings in brackets 34^x secured to one side of the frame 10. 110

The rod 34 has secured thereto a block 35 having a pin 36 extending upwardly therefrom into an elongated socket 37 in one arm of a bell-crank lever 38 pivoted at 39 to one of the brackets 34*. The other arm of the bell-crank lever 38 has an elongated slot 40 therein, in which is positioned a pin 41 extending upwardly from a rod 42 extending transversely of the machine and at the rear thereof, this rod 42 being adapted to reciprocate in bearings 43.

Between the bearings 43, the rod 42 has secured thereto the collars 44, between which and each of the bearings 43 are the helical 15 springs 45.

The rod 42 also has secured thereto the collars 46 between which is disposed the hub of the belt shifting member 47, this hub being keyed to and slideable on the rod 20 42 as indicated in Fig. 1 of the drawings.

The length of the hub of the belt shifting member 47 is considerably less than the space between the collars 46.

Normally, the pins 36 and 41 are centrally 25 positioned in the slots 37 and 40, as indicated in Fig 1 of the drawings.

When the arm 31 approaches its rear-most position, it will come into contact with the collar 33 and move the rod 34 toward 30 the rear. This movement will cause the pin 36 to move along the slot 37, at the same time causing the bell-crank lever 38 to be moved about its pivot 39 so that the wall of slot 40 acting upon the pin 41 will cause 35 the rod 42 to be moved toward the left of the machine, as represented in Fig. 1.

This movement of the rod 42 will shift the belts 48, 49 onto pulleys 22, 23, and at the same time compress the spring 45 at 40 the left of Fig. 1, said spring remaining compressed until the arm 31 moves away from the collar 33.

The compressed spring 45 will then expand, returning the rod 42 to its normal 45 position as indicated in Fig. 1 of the drawings.

During this return movement, the belts 48, 49 upon the pulleys 22 and 23 will prevent the lateral movement of the belt shifting member 47, permitting the rod 42 to be moved freely in the hub of said belt shifting member.

The mechanism will then be in proper 55 position for the machine to operate until such time as the drum approaches its forward position, at which time the arm 31 will contact with the collar 32 on the rod 34, and move said rod lengthwise, effecting such movement of the bell-crank lever 38 60 about its pivot 39 as to move the rod 42 in the opposite direction and shift the belts 48 and 49 onto the loose pulley 22 and fast pulley 24.

It is obvious, therefore, that by means 65 of the mechanism just described, the drum

15, 16 may be reciprocated lengthwise of the machine, the belts upon the driving pulleys being shifted at the end of the reciprocating movement of the drum 15, 16 in each direction.

Beneath the side bars 11* are other side bars 50, to the under faces of which are secured bearings 51 near the rear of the machine.

In these bearings 51 is mounted an oscillating shaft 52, having secured thereto the forwardly extending treadle arms 53, the front ends of which are connected by a foot board 54.

Each treadle arm 53 has pivotally secured thereto, at 55, a T-shaped member 56, the upper portion of which has pivotally connected thereto at 57, 57 one end of the levers 58 pivoted to the side bars 50 at 59, said levers 58 having their opposite ends pivotally connected at 60 to the members 61.

These members 61 have threaded thereto one end of the adjustable member 62, the opposite ends of which are threaded to the member 63 pivotally connected at 64 to the 90 hide supporting frame 65.

This frame 65 is adapted to be moved vertically by means of the treadle mechanism just described, the ends of said frame, during each vertical movement, bearing 95 against the end plates 66 secured to the frame 10.

The hide supporting frame has superimposed thereon the bed 67 which has an extension 68 extending forwardly beyond 100 the front of the frame 10, this extension 68 providing a means whereby the hide may be more readily positioned upon the hide support when it is desired to operate upon the hide.

The upper face of the bed 67 has glued or otherwise secured thereto a sheet of material 69, the upper face of which is adapted to grip upon a hide placed thereon.

The opposite ends of the shaft 14 have 110 secured thereto and revoluble therewith the cam disks 70, each having a shoulder 71 with which a pawl 72 pivotally secured at 73 to a gear 19, 19* is adapted to engage.

The pawls 72 are adapted to be retained 115 in contact with the periphery of the cam disks 70 by means of springs 74.

The rack 18 is positioned above the gear 19 and as the drum is moved toward the rear of the machine, the intermeshing teeth 120 of the rack and gear will cause the gear to be moved in the direction of arrow *a* (Fig. 2).

As the pawl 72 is in engagement with the shoulder 71, the rotary movement of 125 the gear 19 will be imparted to the disk 70 secured to the shaft 14, thus causing the drum to make half a revolution during its rearward movement.

During this rearward movement of the 130

drum 15, 16, the rack 18^x, being beneath the gear 19^x on the opposite end of the shaft 14, will cause the gear 19^x to be moved in a direction opposite to the arrow *a* on Fig. 2, the pawl riding over the periphery of its coacting cam member 70.

When the extreme rearmost position of the shaft 14 is reached, and said shaft begins to return toward the front of the machine to its normal position, the movement of both gears will be reversed and the pawl 72 on the gear 19^x will engage the shoulder 71 of its coacting cam disk 70 and complete the revolution of the drum 15, 16. In other words, by means of this mechanism, the drum 15, 16 makes a complete revolution at each reciprocation thereof, and during the operation of the machine continuously rotates in one direction.

Normally, the hide support 67 is in the position indicated in Fig. 2 of the drawings, and when the drum 15, 16 is at or near the rear end of the frame 10, the operator places a folded hide upon the gripping sheet 69, the fold or bight of the hide being toward the rear of the machine.

When the drum reaches its forward position, the operator presses upon the foot board 54, moving the treadle arms 53 about the pivot 52, and thus forces the hide support with the folded hide thereon upwardly against the drum 15, 16, in which position the hide support 67 is retained until the drum in its reciprocation reaches its rearmost position.

As the drum commences to rotate during the rearward movement of the drum, the hide-gripping sheet 17 thereon will grip upon the adjacent face of the hide and cause it to be moved toward the rear of the machine, the lower layer of the hide being retained in position on the sheet 69 by the friction thereof. As a consequence of this movement, the bight or fold of the hide will be moved toward the rear of the machine until the drum 15, 16 reaches its extreme rearward position.

The operator then removes his foot from the foot board 54 of treadle 53, and the hide support 66 will return, of its own weight, to its normal position.

The operator then seizes the hide and turns it over upon the support 67 and repeats the operation so that the other half of the hide will be treated in the same manner.

By pinching the bight or fold of the hide in this manner a grain will be formed all over the finish side of the hide.

If it is desired to produce a box effect upon the finish side of the hide, the hide will be folded again so that the fold will be at right angles to the fold previously described, and the two operations just mentioned will be repeated.

When a pebbled or fancy effect is preferred, the operations of the hide may be carried still further, with the hide folded at any angle to the folds hereinbefore referred to.

70

It must be understood that when the hide is folded, the finish faces are always inside.

It is obvious, therefore, that by means of this machine any design may be given to the finish faces of the hide that could be secured by hand operation and with less labor and in less time.

It is believed that the operation and many advantages of the invention will be understood readily without further description.

Having thus described my invention, I claim:

1. In a machine of the class described, a hide support consisting of a rigid table supported at opposite ends and fixed as to end movement; guides above and parallel to said support; blocks reciprocable lengthwise of and between said guides; a shaft mounted in bearings in said blocks; screw mechanism for reciprocating said blocks; a drum secured to said shaft and adapted to coat with material on said support; and positive means for rotating said drum during its reciprocation with said blocks.

2. In a machine of the class described, a hide support; guides parallel to said support; blocks reciprocable lengthwise of said guides; a shaft mounted in bearings in said blocks; screw mechanism for reciprocating said blocks including reciprocating members having formed integral therewith bearings for the opposite ends of said shaft; a drum secured to said shaft; gears loosely mounted on said shaft; stationary racks meshing with the gear teeth; and connections between the gears and the drum shaft for imparting to said shaft a complete rotation during each reciprocation of said blocks.

3. In a machine of the class described, a frame having side bars and guides; a hide support; revoluble screws parallel with said support; blocks reciprocable lengthwise of said guides; reciprocable members threaded to and movable lengthwise of said screws and having bearings for said shaft; a shaft rotatably mounted in bearings in said blocks and said reciprocable members; a drum secured to said shaft; cam members secured to said shaft; gears loosely mounted on said shaft; racks on said bars engaging the teeth of said gears; mechanism for rotating said screws; and pawls on said gears engaging shoulders on said cam members.

4. In a machine of the class described, a hide support; screws parallel to said support; members threaded to and reciprocable lengthwise of said screws; a shaft mounted in bearings in said members; mechanism for

80

130

rotating said screws; a drum secured to said shaft; positive means for rotating said drum during its reciprocation with said members and means for reversing the rotation of said screws at the end of movement of said members in either direction.

5. In a machine of the class described, a hide support; screws parallel to said support; members threaded to and reciprocable lengthwise of said screws; a shaft mounted in bearings in said members; parallel guides on said frame; blocks surrounding said shaft and reciprocable between said guides; a drum secured to said shaft; gears loosely mounted on said shaft; stationary racks meshing with the gear teeth; and connections between the gears and the drum shaft for imparting to said shaft a complete rotation during each reciprocation of said blocks.

6. In a machine of the class described, a frame having side bars and parallel guides; blocks reciprocable between said guides; a hide support; revoluble screws parallel with said support; members threaded to and movable lengthwise of said screws; a shaft rotatably mounted in bearings in said blocks and members; a drum secured thereto; cam members secured to said shaft; gears loosely mounted on said shaft; a rack on one of said bars above one of said gears and engaging the teeth thereof; a rack on another bar below the other gear and engaging the teeth thereof; mechanism for rotating said screws; and pawls on said gears adapted to engage shoulders on said cam members.

7. In a machine of the class described, a hide support; screws parallel to said support; members threaded to and reciprocable lengthwise of said screws; a shaft mounted in bearings in said members; positive mechanism for rotating said screws; a drum secured to said shaft; mechanism for imparting a half revolution to said drum during its movement in one direction; another mechanism for completing the revolution of said drum while moving in the opposite direction; and means for reversing the rotation of said screws at the end of movement of said members in either direction.

8. In a machine of the class described, a hide support; screws parallel to said support; members threaded to and reciprocable lengthwise of said screws having shaft bearings formed integral therewith a shaft mounted in bearings in said members; a drum secured to said shaft; two gears loosely mounted on said shaft; stationary racks meshing with the gear teeth, one rack being positioned above one gear and the other below the second gear; and connections between the gears and the drum shaft for imparting to said shaft a complete rotation during each reciprocation of said members.

9. In a machine of the class described, a hide support; guides parallel to said support; blocks adapted to reciprocate on said guides; a drum supported on said blocks; means for rotating said drum, other members reciprocable with said blocks having bearings for the opposite ends of said shaft; revoluble screws for reciprocating said members and blocks; a reciprocating rod; collars thereon; means reciprocable with said blocks and coacting with said collars to move said rod endwise; a driving shaft perpendicular to said screws; fast and loose driving pulleys thereon for controlling the rotation of said screws; a belt shifting member; and mechanism actuated by said rod for imparting movement to said belt shifting member.

10. In a machine of the class described, a hide support; guides parallel to said support; blocks adapted to reciprocate on said guides; a drum supported on said blocks; means for rotating said drum, other members reciprocable with said blocks having bearings for the opposite ends of said shaft; revoluble screws for reciprocating said members and blocks; a drive shaft perpendicular to said screws; gears for rotating said screws from said shaft; fast and loose pulleys on said shaft; a belt shifting member; a reciprocating rod; collars thereon; means reciprocable with said blocks and coacting with said collars to move said rod endwise; and crank mechanism actuated by the movement of said rod for imparting movement to said belt shifting member.

11. In a machine of the class described, a hide support; guides parallel to said support; blocks adapted to reciprocate on said guides; a drum provided with a shaft supported in bearings on said blocks; means for rotating said drum, other members reciprocable with said blocks having bearings for the opposite ends of said shaft; revoluble screws for reciprocating said members and blocks; a drive shaft perpendicular to said screws; gears for rotating said screws from said shaft; fast and loose pulleys on said shaft; a belt shifting member; a reciprocating rod; collars thereon; a nut on one of said screws reciprocable with said blocks and provided with an arm coacting with said collars to move said rod endwise; and crank mechanism actuated by the movement of said rod for imparting movement to said belt shifting member.

12. In a machine of the class described, a hide support; guides parallel to said support; blocks adapted to reciprocate on said guides; a drum supported on said blocks; means for rotating said drum, other members reciprocable with said blocks having bearings for the opposite ends of said shaft; revoluble screws for reciprocating said members and blocks; a drive shaft perpen-

dicular to said screws; gears for rotating said screws from said shaft; fast and loose pulleys on said shaft; a belt shifting member; a reciprocating rod; collars thereon; 5 means reciprocable with said blocks and co-acting with said collars to move said rod endwise; and mechanism, including a pivoted bell-crank lever, actuated by the move-

ment of said rod for imparting movement to said belt-shifting member. 10
